Primary Examiner — Garth Rademaker

Assistant Examiner — Suzanne E Tisdell

(57) **CLAIM**

The ornamental design for a steering wheel cover, as shown and described.

DESCRIPTION

1. Steering wheel cover

1.1 : Perspective

1.2 : Front

1.3 : Back

1.4 : Left

1.5 : Right

1.6 : Top

1.7 : Bottom

1.8 : Perspective

Fig. 1.1 is a perspective view of a steering wheel cover, showing my new design; fig. 1.2 is a front elevational view thereof; fig. 1.3 is a rear elevational view thereof; fig. 1.4 is a left elevational view thereof; fig. 1.5 is a right elevational view thereof; fig. 1.6 is a top plan view thereof; fig. 1.7 is a bottom plan view thereof; fig. 1.8 is another perspective view thereof; the broken lines where present illustrate portions of the steering wheel cover that form no part of the claimed design.

1 Claim, 8 Drawing Sheets
